CLAIM

The ornamental design for a holder for fixing dental block, as shown and described.

DESCRIPTION

FIG. 1 is a top perspective view of a first embodiment of a holder for fixing dental block showing the new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a top perspective view of second embodiment of a holder for fixing dental block showing the new design;

FIG. 10 is a bottom perspective view thereof;

FIG. 11 is a front view thereof;

FIG. 12 is a rear view thereof;

FIG. 13 is a right side view thereof;

FIG. 14 is a left side view thereof;

FIG. 15 is a top plan view thereof; and,

FIG. 16 is a bottom plan view thereof.

The broken lines show portions of the holder for fixing dental block that form no part of the claimed design. The lines consisting of long lines and dots indicate conceptual border lines between the claimed portion and the disclaimed portion.
